UNITED STATES PATENT OFFICE

FREDERICK J. O'BRIEN, OF TITUSVILLE, PENNSYLVANIA, ASSIGNOR TO STRUTHERS
WELLS-TITUSVILLE CORPORATION, OF TITUSVILLE, PENNSYLVANIA, A CORPORA-
TION OF DELAWARE

LIFTING DEVICE FOR PIPE SLIPS

Application filed January 19, 1929. Serial No. 333,538.

This invention relates to a lifting device designed more particularly for use with the jaws or slips employed in connection with the pipe or casing of oil well drilling apparatus.

5 One of its chief objects is the provision of a lifting device of this character which is simple, compact and inexpensive in construction, and which is so organized and arranged as to materially facilitate the movement of 10 the slips into and out of their operative position with a minimum of effort.

A further object of the invention is to provide a pipe slip lifting device which may be readily attached to and removed from the 15 rotary tables of oil drilling equipment now in use and which does not require the use of separate fastenings to anchor it to such table.

In the accompanying drawings:—

20 Figure 1 is a sectional side elevation of the rotary table of a drilling apparatus showing my lifting device applied thereto. Figure 2 is a fragmentary top plan view thereof. Figure 3 is a section side elevation, similar 25 to Figure 1, showing the pipe slips withdrawn from their gripping position. Figure 4 is a perspective view of the supporting frame of the lifting device.

Similar characters of reference indicate 30 corresponding parts throughout the several views.

By way of example, my invention has been shown in connection with an oil drilling apparatus of the rotary type, 10 indicating the 35 rotary table and 11 the table-bushing having the customary tapered opening 12 through which the pipe or casing 13 extends. This casing is held suspended from the table-bushing by suitable pipe slips 14 seated in 40 the tapered opening thereof, the slip unit shown in the drawings consisting of two half sections, each section being composed of a plurality of jointed sectors to enable the slips to accommodate themselves in gripping 45 the surface of the casing.

In order to effect the ready insertion and removal of the slips into and out of the opening 12 in the table-bushing and with little effort, I employ a lifting device which is composed essentially of a frame or support de-

tachably mounted on the top side of the rotary table 10 and pivoted carriers for the slip-sections movable relatively to the support for lowering and raising such sections into and out of their operative position, there being a companion support and carrier for each half section of the slip unit.

The frame or support of the lifting device, indicated generally by the numeral 15, consists of substantially U-shaped members shaped from flat bar stock or otherwise and applied to the top of the table on diametrically opposite sides thereof with their open ends facing each other, as seen in Figure 2. The free ends of the parallel arms 16 of each frame terminate in depending hook-shaped lugs 17 adapted to engage corresponding openings 18 in the top wall of the table-bushing 11, as shown in Figures 1 and 2. The hooked-ends of these lugs interlock with the undersides of the companion openings to prevent vertical displacement of the frame. In applying the latter to the bushing, it is held in a substantially upright position with the hooked ends thereof engaged with the openings 18, after which the frame is swung to its horizontal position overlying the table.

Journalized in each frame adjacent the closed end thereof is a transversely-disposed 80 rock shaft 19 provided at one end with a crank or handle 20 extending toward the axis of the rotary table 10 and normally overlying the same. As shown in Figure 2 the handle of one frame is disposed at one side 85 of the slips 14 and the handle of the other frame is disposed on the opposite side thereof, so that both handles may be operated conveniently without interference. Fixed on each rock shaft by pins 21 or otherwise, to turn 90 therewith are suspension arms or levers 22 which extend inwardly from the shaft and have their inner ends curved downwardly into the upper end of the opening 12 in the table-bushing 11, as shown in Figure 1. 95 These suspension arms are pivoted at 23 to the upper ends of links 24 whose lower ends are pivoted at 25 to lugs or projections 26 rising from the companion slip-section. This pivoted-link or flexible suspension arrange- 100

ment enables the slip-sections to independently adapt themselves to the surface of the pipe casing and at the same time facilitates their insertion and removal into and out of the opening of the table-bushing in a more or less pendant position as the respective rock shafts 19 are turned in one direction or the other. This construction also prevents binding of the slip-sections during their raising and lowering movements and in no way interferes with the self-centering of the sections in the table-bushing opening.

While this device has been shown and described in connection with the lifting of pipe slips, it is to be understood that it can be used equally as well with casing spiders, elevators and the like.

I claim as my invention:—

1. In a lifting device for pipe slips, the combination with the table and the table-bushing of a rotary drilling apparatus, said bushing having openings in its top wall, of supports arranged on diametrically opposite sides of the table and having hook-shaped lugs thereon for detachably interlocking with the openings in said table-bushing, vertically-swinging carriers fulcrumed on said supports in opposing relation to each other, and pipe-gripping elements having attaching lugs rising therefrom and flexibly connected to the free ends of said carriers.

2. In a lifting device for pipe slips, the combination with the table and the table-bushing of a rotary drilling apparatus, said bushing having openings in its top wall, of supports arranged on diametrically opposite sides of the table and having hook-shaped lugs thereon for detachably interlocking with the openings in said table-bushing, rock shafts journaled on said supports and each provided at one end with a handle for actuating them, vertically-swinging suspension arms fixed on said shafts, pipe-gripping members having lugs rising from their top sides, and links pivotally connecting said lugs with said suspension arms.

FREDERICK J. O'BRIEN.
